UNITED STATES PATENT OFFICE.

WALTER G. SAHLIN, OF BOSTON, MASSACHUSETTS.

HAND VISE.

1,402,893.

Specification of Letters Patent. Patented Jan. 10, 1922.

Application filed February 28, 1921. Serial No. 448,580.

To all whom it may concern:

Be it known that I, WALTER G. SAHLIN, of Boston, in the county of Suffolk and State of Massachusetts, a citizen of the United States, have invented a new and useful Improvement in Hand Vises, of which the following is a specification.

My invention relates to an improvement in hand vises whereby the movable jaw is enabled to grasp the work more securely and hold it more firmly than any such vise of which I have knowledge, because the opposing faces of the jaw are maintained in parallel relation and hence clamp the work with equal force wherever the jaws touch it.

My invention will be understood by reference to the drawings in which it is shown in its preferred form.

Figure 1 is a side elevation of a vise embodying my invention.

Fig. 2 is a section on line 2—2 of Fig. 3.

Fig. 3 is a plan.

Figs. 4 and 5 are sections on lines 4—4 and 5—5, respectively, of Fig. 2.

My invention comprises a stationary jaw which is L-shaped in side elevation, 1 being the jaw proper and 2 a base having a longitudinal slot 3 therein and a longitudinal groove 31 on its under side. The movable member comprises a movable jaw 4, a base or slide piece 5 therefor and a clamp 6, these parts being held on the base 2 of the stationary jaw by a bolt 7 the head of which slides in the groove 31, its body passing up through holes in the slide piece 5 and clamp 6, a nut 8 holding the parts together. The slide piece 5 has a guide 9 on its under surface of sufficient width to fit the slot 3 so as to hold the jaws in parallel relation.

The rear surface of the jaw 4 slants as at 10 and the front face of the slide piece is correspondingly shaped except at its middle portion where it has a tongue 11 which fits into a recess in the jaw 4. A pin 12 passing through the slide piece 5 and tongue 11 holds these two parts in proper relation. The pin 12 is preferably cut away as 13 and its ends are slightly smaller than the opening in which they lie so that the jaw 4 may move slightly under pressure with relation to the slide piece.

The rear upper face of the slide piece 5 has a groove 14 to receive the correspondingly-shaped tail piece 15 of the clamp 6. The front end of the clamp has arms 16 which lie in recesses 17 in the jaw 4, these

parts being so shaped and proportioned that the clamp will be held normally out of contact with the top by the slide piece 5 and may be rocked slightly by the tightening of the nut 8.

In practice the work is placed between the two jaws 1 and 4 and the jaw 4 being moved up against the work as close as may be by hand, the nut 8 is tightened and as it bears down on the clamp 6 it rocks it around its tail piece 15 and the arms 16 depress the jaw 4 so that, as by a cam action, it is driven downwardly and slides on the slanting surface 10 in a direction toward the stationary jaw 1, the difference between the diameter of the ends of the pin 12 and the openings in the slide piece being sufficient to allow this movement.

It will be seen that the clamping of the movable jaw by the bolt and clamp not only holds the slide piece in fixed relation to the base, but also drives the movable jaw toward the stationary jaw in a fixed parallel relation thereto because of the cam-shaped surfaces at 10. For this purpose the bottom of the movable jaw 4 in its normal position as shown at 18 does not touch the base 2, but may have a slight downward movement with relation thereto.

I do not mean to limit myself to the exact embodiment of my invention shown as it may be otherwise embodied, so that the movable jaw may by the same movement be clamped to the base and moved toward the stationary jaw.

What I claim as my invention is:

1. A vise comprising a base, a stationary jaw mounted thereon, a movable jaw, and means whereby said movable jaw may be clamped to said base and simultaneously moved toward said stationary jaw, said means comprising a slide piece having a cam surface, said movable jaw having a corresponding cam surface, and means for clamping said jaw against said slide piece and said base.

2. In a vise, a base, a stationary jaw, a movable member adjustably mounted on said base, said movable member comprising a slide piece, a jaw mounted thereon, the face of said jaw being in parallel relation with the face of said stationary jaw, a clamp and means for compressing said clamp against said base, said slide piece and said jaw having co-operating surfaces whereby when said movable member is clamped

against said base said movable jaw will be moved toward said stationary jaw.

3. In a vise, a base, a stationary jaw having a holding surface and a movable member comprising a slide piece having a face slanting toward said stationary jaw, a movable jaw having a holding surface opposite and in parallel relation to the holding surface of said stationary jaw and having a 10 face adapted to engage the slanting face of said slide piece, and means for clamping said slide piece to said jaw whereby pressure in said jaw will cause it to slide down said slanting face and its holding surface to ap-

proach the opposing holding surface of said 15 stationary jaw.

4. In a vise, a base, a stationary jaw and a movable member comprising a slide piece, a movable jaw mounted thereon and hinged thereto and a rockable clamp piece one edge 20 of which engages said slide piece and the other end of which engages said movable jaw, and a bolt passing through said base, said slide piece and said clamp and adapted to clamp said movable member to said base 25 and move said movable jaw toward said stationary jaw.

WALTER G. SAHLIN.
